UNITED STATES PATENT OFFICE.

THOMAS D. COOPER, OF CROSS ROADS, AND SAM LAW, OF HERMIT HOLE,
ENGLAND.

TOY CANNON.

SPECIFICATION forming part of Letters Patent No. 650,633, dated May 29, 1900.

Application filed August 29, 1899. Serial No. 728,825. (No model.)

To all whom it may concern:

Be it known that we, THOMAS DAVEY COOPER, a resident of Cross Roads, and SAM LAW, a resident of Hermit Hole, both near 5 Keighley, in the county of York, England, subjects of the Queen of Great Britain, have invented a new or Improved Toy Cannon, of which the following is a specification.

Our invention relates to a new or improved toy cannon, and has for its object the production of a cannon and parts in connection therewith of such construction as to fit same for the exercise of skill and judgment on the part of the user when desirous of hitting a given 5 mark by the projectile. To attain this object, we make use of the means and devices hereinafter described, and illustrated by the accompanying sheets of drawings, which form part of this specification, and wherein—

Figures 1 and 2 are an elevation and a longitudinal section of a cannon and parts in connection therewith made in accordance with our invention. Fig. 3 is a plan of parts shown by Figs. 1 and 2. Figs. 4 and 5 are an elevation and a plan, respectively, of a modified device by which the force for sending the projectile may be transmitted, as hereinafter described. Figs. 6 and 7 are an elevation and a plan illustrating in detail means whereby the 50 cannon may be adjusted in position. Fig. 8 is an elevation illustrating a modified form of means for adjusting the cannon in place of those shown by Figs. 6 and 7.

In carrying our invention into effect we 55 mount the barrel *a* upon its pivotal bearings *b* in the well-known manner, its inclination thereon to the horizontal plane being either effected and regulated by the wedge *c*, Fig. 8, which is old and well known, or the arm *d*, having a spring *e* and bolt *f*, which forces it 60 against the side of the bearings *b* to cause sufficient friction between them to enable said arm *d* to maintain and support the barrel *a* in whatever position or inclination it may be placed or made to assume.

In the breech of the barrel *a* is detachably mounted the plug *g*, through which air is conducted by the tube *h* when forced from the flexible (as india-rubber) ball *k*.

To bring the cannon into use, the plug *g*

is removed, and the projectile or dart *m* is inserted at the breech of the barrel *a*, (see Fig. 2,) on which the plug *g* is replaced. The barrel *a* is then adjusted and directed toward the target or point aimed at, and when ready 55 the projectile *m* is forced from it by the user striking the ball *k* with his hand. The force of the blow thus given relatively with the space through which the projectile has to travel before hitting the point aimed at, as 60 well as the adjustment of the barrel in proper position, entails the exercising of more skill than would be the case were the force transmitted by the air to be effected by means that might be more accurately regulated. 65

The interior or bore of the barrel *a* is lined with glass or other smooth substance to reduce friction, while the sighting-pieces *p* are mounted on said barrel to enable it to be directed as desired, the piece *p* being preferably movable in a lateral direction in the slot *x* for adjustment when manufacturing the barrel.

It will be seen that instead of striking the ball *k* directly with the hand an interceding 75 lever *v* may be mounted at *w* to the bearings *x* to receive the blow, while a spring *v'* is employed for bringing said lever *v* into its normal position when free.

Such being the nature and object of our invention, what we claim is—

1. In a toy cannon, a pivotally-supported barrel, in combination with a pivotally-supported arm the outer end of which extends under the barrel, spring mechanism for frictionally holding the arm to control the elevation of the barrel, and means for forcing a current of air through said barrel. 85

2. In a toy cannon, the combination with a pivotally-supported barrel, of a detachable 90 plug fitting the breech of the barrel, air-forcing means, and a flexible air-conduit between said air-forcing means and the plug.

In testimony whereof we have affixed our signatures in presence of two witnesses.

THOMAS D. COOPER.
SAM LAW.
